[57] CLAIM

The ornamental design for a ball game target gate, as shown and described.

DESCRIPTION

FIG. 1 is a perspective view of a ball game target gate showing our new design;

FIG. 2 is a front elevational view thereof; the rear elevational view being a mirror image thereof;

FIG. 3 is a top plan view thereof;

FIG. 4 is a bottom plan view thereof;

FIG. 5 is a left side elevational view thereof; the right side elevational view being a mirror image thereof; and,

FIG. 6 is a perspective view thereof, in it's environmental use showing the target in an alternate position.

The broken line showing of a ground is for illustrative purposes only and forms no part of a claim.
